UNITED STATES PATENT OFFICE.

WILLIAM H. NEEDHAM, OF WORCESTER, MASSACHUSETTS, ASSIGNOR TO BOSTON
PRESSED METAL CO., OF WORCESTER, MASSACHUSETTS, A CORPORATION OF
MAINE.

LAST-THIMBLE.

1,327,839.

Specification of Letters Patent.

Patented Jan. 13, 1920.

Application filed January 21, 1919. Serial No. 272,346.

To all whom it may concern:

Be it known that I, WILLIAM H. NEEDHAM, a citizen of the United States, residing at Worcester, in the county of Worcester and 5 State of Massachusetts, have invented a new and useful Last-Thimble, of which the following is a specification.

This invention relates to a last thimble, and particularly to an improved construction by which the bottom or end of the thimble may be strengthened and reinforced.

Such thimbles are inserted in the heel portion of a wooden shoe last and are designed particularly to receive the pin by which the 15 last is located in a heel-setting or other machine. If this pin is a little too long, it will engage the bottom of the thimble, under which condition the heavy pressure developed in the heel-setting operation frequently 20 forces the rounded end of the pin directly through the end of the thimble. To prevent this result, last thimbles have been heretofore provided with thickened end portions to resist this excessive pressure.

25 My present invention relates to improvements in the construction of last thimbles having such thickened end portions.

My invention further relates to certain arrangements and combinations of parts hereinafter described and more particularly 30 pointed out in the appended claims.

Preferred forms of my invention are shown in the drawings, in which

Figure 1 is a sectional view of my improved last thimble, inserted in a shoe last;

Fig. 2 shows the thimble at an intermediate stage in its production;

Fig. 3 represents a later step in the operation of forming the thimble;

40 Fig. 4 is a sectional view of the reinforcing disk, and

Figs. 5 and 6 are sectional views of modifications.

Referring to the drawings, it will be seen 45 that my improved thimble comprises a cylindrical casing 10 having a flanged end 11 and an inwardly projecting end portion or bottom 12; this end portion, in the form shown in the drawings, entirely closing the inner 50 end of the thimble. The complete thimble also includes a disk 13 secured within the casing 10 and reinforcing the end portion 12.

In the production of this thimble, a cylindrical shell with a closed bottom is first 55 formed from a flat piece of sheet metal by a

succession of well-known drawing operations. These operations are repeated until a shell is produced which is slightly larger in diameter than the finished thimble. Such a shell is illustrated at 10^a in Fig. 2. In the 60 preferred process of finishing and reinforcing the shell 10^a, a disk 13, concaved as shown in Fig. 4, is placed upon the upper end of an inverted punch 14 (Fig. 2), and the shell 10^a is then placed over the disk 65 and punch. The upper end of the punch may be concaved to receive the convex side of the disk, and it will be noted that the diameter of the disk 13 is slightly greater than the diameter of the punch 14.

A die 15 is then forced downward over the shell 10^a, forming therefrom the finished casing 10 fitting the punch 14. In so doing, the metal of the side wall of the shell is contracted around the edge of the disk 13 which 75 thus becomes embedded in the metal and is thereafter held firmly in position against the bottom or end portion 12 of the casing 10.

At the same operation, or if preferred at a 80 later operation, the end portion 12 may also be concaved to correspond to the arched shape of the disk 13, the thimble then presenting the finished form shown in Fig. 1.

With this construction it will be seen that 85 the disk 13 is firmly secured in place by the final drawing operation which completes the casing and without any additional operation. Furthermore, the concaved or arched shape of the disk 13 more firmly resists the 90 action of a pin engaging therewith, as any pressure applied in an upward direction against the disk 13 as viewed in Fig. 1, has a tendency to flatten and thus enlarge the disk 13, thereby causing it to be even more 95 firmly secured in place.

In Fig. 5, I have shown a thimble 16 having a rounded instead of a concaved end, and reinforced by a correspondingly shaped disk 17. This disk is embedded in the casing wall as in the preferred form, and the construction retains many of the advantages heretofore described.

The form shown in Fig. 6 utilizes a flat 100 disk 18 which is shown as having a thin cylindrical flange 19 embedded in the casing wall 20. This flange assists in retaining the disk in place, and its use is optional on all forms of disk. Conversely, the flat disk may 105 be used without the flange.

110

Having thus described my invention and certain modifications thereof, it will be evident that further changes and modifications both in the article and in the process may 5 be made by those skilled in the art without departing from the spirit and scope of my invention as set forth in the claims, and I do not wish to be otherwise limited to the details herein disclosed, but what I claim is—
10 1. A last thimble having, in combination, a cylindrical casing with an end portion and a reinforcing disk secured within said casing and against said end portion, said disk having its edge embedded in the side wall of
15 said casing.
2. A last thimble having a cylindrical casing with a thickened end portion, said end portion being concaved to form an inwardly arched bottom for said thimble.

3. A last thimble having, in combination, 20 a cylindrical casing with a closed end and a reinforcing disk secured within said casing and against said end, said disk and end being both concaved to form an inwardly projecting arched bottom for said thimble.

4. A last thimble having, in combination, 25 a cylindrical casing with an inwardly projecting end portion and a reinforcing disk slightly larger in diameter than the finished inside diameter of said thimble and held firmly in position within said casing and against said end portion by the inwardly overlapping material of the cylindrical casing wall.

In testimony whereof I have hereunto 30 affixed my signature.

WILLIAM H. NEEDHAM.
